DRILL FOR FORMING SOLIDIFIED CORE PILES

Odie Colquitt, Denver, Colo., assignor to The Winter-Weiss Co., Denver, Colo., a corporation of Colorado

Application February 13, 1953, Serial No. 336,727

1 Claim. (Cl. 255—61)

1

This invention relates to a drill for forming solidified core piles. Solidified core piles are formed by loosening a vertical core of earth and saturating the loosened core with a solidifying solution, such as sodium silicate compounds or the like, thence allowing the saturated, loosened earth to become solidified as a cylindrical core within the surrounding earth.

It has been difficult to drill the loosened earth cores for since the earth is not removed, it is difficult to withdraw the drill after the drilling is completed.

The principal object of this invention is to provide a drill for drilling loosened earth core for solidified core piles which will enable the operator to quickly and easily detach a drill stem from an inexpensive drill head after the drilling is completed so that the stem may be easily withdrawn, leaving the head in place.

Another object of the invention is to provide a detachable drill head in which all mechanically operated locking and unlocking means will be eliminated, and in which the head may be detached by the simple action of the hydraulic pressure of the core fluid.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved solidified earth core drill;

Figs. 2, 3, and 4 are horizontal cross-sections, taken on the lines 2—2, 3—3, and 4—4, respectively;

Fig. 5 is a vertical, longitudinal section, taken on the line 5—5, Fig. 1, illustrating the drill in the working position; and

Fig. 6 is a similar section, illustrating the improved drill in the detached or released position.

In the drawing, the improved drill is illustrated mounted on the lower extremity of a tubular drill stem 10 which extends to any suitable rotary device at the surface for rotating the drill. When in use, the drill stem is connected to a suitable fluid supply at the surface for feeding core solidifying solution through the hollow stem.

The drill comprises a cylindrical barrel 11 having a threaded socket into which the lower ex-

2

tremity of the drill stem 10 is threaded. The internal diameter of the barrel 11 is reduced below the drill stem 10 to form a reduced axial fluid passage 12, and the lower extremity of the barrel 5 extends telescopically into a drill sleeve 13.

A drilling blade 14 is welded or otherwise secured diametrically across the lower extremity of the drill sleeve 13 and projects oppositely outward therefrom. The lower edge of the drilling 10 blade 14 is provided with beveled cutting teeth 15 arranged in staggered arrangement on opposite sides of the axis. A transverse key pin 16 extends diametrically of the lower extremity of the sleeve 13 and is welded or otherwise permanently secured therein. The blade 14 is notched to receive the lower extremity of the sleeve 13, and the pin 16 is positioned below the upper edge of the blade 14.

The bottom of the barrel 11 is provided with 20 oppositely positioned notches 17 to receive the pin 16 as shown in Fig. 5. Thus, when the barrel is forced downwardly in the sleeve 13, the pin 18 will rest in the notches 17, so that the rotation of the barrel will be imparted to the sleeve 13 and 25 to its blade 14 to cause the latter to drill a cylindrical core of loosened earth.

The sleeve 13 is normally supported on the barrel 11 by means of two free locking balls 18 which are positioned in ball openings 19 in the barrel, and which may extend outwardly into a ball-receiving groove 20 in the sleeve 13. The balls 18 are forced outwardly into the receiving groove 20 by means of an internal, hollow plunger 21 formed with a peripheral shoulder 22 which, when the 30 plunger moves upwardly, forces the two balls 18 outwardly into the groove 20.

The plunger is provided with an upper portion 23 of reduced diameter which slides within the fluid passage 12. The upper extremity of 40 the portion 23 contains an open conical ball valve seat 30. The diameter of the upper portion 23 will allow the balls 18 to move inwardly in their ball openings 19 sufficiently to release them from the ball-receiving groove 20.

The plunger is constantly urged upwardly in the barrel 11, and the barrel 11 is constantly urged downwardly on the plunger 21, by means of a spiral compression spring 24 which surrounds the lower extremity of the plunger and is compressed between a spring shoulder 25 on the latter and a spring bushing 26. The spring bushing 26 is threaded into the lower extremity of the barrel 11 and the lower extremity of the plunger 55 21 is slidably therewithin. Leakage around the

plunger is prevented by an upper sealing gasket 27 and a lower sealing gasket 28.

During the drilling operation, the mechanism is in the position of Fig. 5. Let us assume, that the drill stem 10 is rotating and that fluid of a type to solidify earth is being pumped down the drill stem and through the hollow plunger 21 to the drilling blade 14. The latter scrapes away and loosens a cylindrical core of earth and intermixes this loosened earth with the solution flowing through the drill stem. When the desired depth has been reached, a core of solution-saturated earth will surround the drill stem 10, the barrel 11 and the sleeve 13, and completely cover the drilling blade 14 so as to make removal of the latter extremely difficult if not impossible.

The present invention, however, enables the operator to quickly detach the drilling blade from the remainder of the drill so that the latter may be easily withdrawn to allow the core to solidify into a solid pile of earth on the drill blade and sleeve. This is accomplished by simply dropping a loose steel check ball 29 down the drill stem 10 onto the conical valve seat 30 in the upper extremity of the plunger 21 as shown in Fig. 6.

Pressure is now applied to the fluid in the drill stem 10 to cause the latter to act against the ball 29 to compress the spring 24 and force the plunger and the barrel 11 in opposite directions. This brings the reduced upper portion 23 of the plunger to a position opposite the balls 18, as shown in Fig. 6, and allows the balls to move radially inward to release them from the ball groove 20. This completely disconnects the barrel 11 from the sleeve 13 and allows the drill stem and the casing to be pulled upwardly through the saturated core, leaving the sleeve 13 and the drill blade 14 embedded.

Therefore, there is a loss of one drill blade for each core formed. However, the time saved and the assured recovery of the casing and its contained mechanism will more than offset the loss of the comparatively inexpensive drill blade.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

An earth boring drill bit adapted to be mounted on the lower extremity of a hollow rotary drill stem comprising: a vertical sleeve; a tubular barrel adapted to be secured on said drill stem and extending into said sleeve; a latch ball positioned in an opening in said barrel and adapted to extend outwardly into a receiving groove in said sleeve to prevent longitudinal movement of said sleeve on said barrel; a tubular plunger slidably mounted in said barrel in contact with said ball, said plunger, barrel and sleeve being normally open for the passage of fluid from said stem, said plunger increasing in diameter below said ball so that when forced upwardly it will force said ball outwardly from said barrel into said receiving groove to secure said sleeve to said barrel; a diametrically extending key pin positioned in and extending across the lower extremity of said sleeve; oppositely positioned notches formed in the bottom of said barrel, said notches receiving said pin and preventing relative rotation between said sleeve and said barrel; an annular bushing threaded into said barrel above said notches, said plunger extending downwardly through said bushing; a spring compressed between said bushing and a shoulder on said plunger; means for closing the fluid passage through said plunger when desired so that the pressure of said fluid against said plunger will force the latter downwardly against the action of said spring to allow said ball to move inwardly to release said sleeve from said barrel when desired; and a drilling blade secured across the lower extremity of said sleeve and projecting radially and oppositely outward therefrom.
